[57] **CLAIM**

The ornamental design for a saddle attachment for protecting leg and calf, as shown and described.

DESCRIPTION

FIG. 1 is a front view of a right leg saddle attachment according to the invention showing my new design;

FIG. 2 is a right view thereof;

FIG. 3 is a top plan view thereof;

FIG. 4 is a left plan end view thereof;

FIG. 5 is a left rear view thereof; and,

FIG. 6 is a bottom view thereof.

The dashed lines in FIGS. 1, 2, and 7 represent conventional stitching.

FIG. 1

FIG. 2

FIG. 3

FIG. 4

FIG. 5

FIG. 6
